UNITED STATES PATENT OFFICE

2,445,412

BOX FASTENING MEANS

William Trogman, Chicago, Ill.

Application October 14, 1944, Serial No. 558,655

1 Claim. (Cl. 229—47)

1

This invention relates to boxes, especially of the type known as merchandising boxes, in which there are two box sections arranged in interfitting latched relation with respect to each other and provided with a handle to facilitate carrying the box about.

The invention has for its principal object the provision of an improved construction of this character which will be highly efficient in use and economical in manufacture.

One of the principal objects of the invention resides in the novel latching means for box sections.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of the box embodying my invention showing the same in a partially open position;

Fig. 2 is a perspective view of the same showing the box sections in interfitting relation;

Fig. 3 is a fragmentary top plan detail view, partly in section of the same taken substantially on line 3—3 of Fig. 2;

Fig. 4 is a fragmentary sectional detail view of the same taken substantially on line 4—4 of Fig. 2; and

Fig. 5 is a fragmentary sectional detail view of adjacent wall sections of the box showing the relationship of the latch structure with respect thereto.

Referring more particularly to the drawings, my improved box comprises two interfitting box sections 10 and 11, the box being indicated generally at 12. The section 10 has a wall portion 13, and in this wall portion 13 in a direction from the edge 14 thereof is formed a recess 15 from which preferably though not necessarily are two lateral recesses 16.

The section 11 has a wall portion 17 provided with a slot or slit 18 through which is hooked a handle bar 19 having lateral extensions 20 which engage beneath the wall 17 when a box is being carried about.

The recess 15 provides a tab 18' which preferably, though not necessarily, is insertable through the slit 18 whereby to provide a reinforcement for the adjacent portion of the wall 17 which receives the greatest strain due to a weight in the box when the box is being carried about by the handle.

2

Formed in the wall 17 are oppositely disposed slits or apertures 21, and these slots or apertures 21, which may be referred to as slots, are in registration with the slots or lateral recesses 16, which likewise may be termed slots.

The box sections when arranged in interfitting relation are releasably latched together by means of oppositely disposed latches 22. Each of these latches 22 is substantially U-shaped in form, with the limb 23 thereof insertable through the adjacent registering slots 16 and 21. The opposite limb portion 24 is provided with a finger piece 25 which facilitates removal of the latch from a latched position, and this limb portion 24 is provided with a kink or rib 26 which bears against the adjacent portion of the wall 13.

The latch is formed of spring material so as to frictionally embrace adjacent portions of the wall 13 and 17. To assist in this frictional contact between the latch and the adjacent walls 13 and 14, in forming the slot 21 a spring tab 27 results, and this tab, as shown in Fig. 4, bears against the adjacent limb 23 and thereby assists in frictionally retaining the latch in position.

25 In carrying my invention into effect, it is to be understood that the shape, size, number and location of the slots 16 and 21 are not in limiting character and should not be considered as such. This is also true with reference to the

30 form of the limb portion 24 and the material from which it is formed, except that it is desirable that the latch be U-shaped and be of resilient material. The latch may be formed of round or flat material and in such a manner so

35 long as it frictionally embraces adjacent portions of the walls 13 and 17 for the purposes herein stated. By the same token the construction of the box sections 17 does not enter into my invention, as the construction of these box sections, and especially the manner in which they are hinged or otherwise attached together for movement from and into interfitting relation, may vary in form and design as well as structure without destroying the utility and usefulness of

40 my invention.

While I have illustrated and described the preferred form of construction for carrying my invention into effect, this is capable of variation and modification without departing from the 45 spirit of the invention. I, therefore, do not wish to be limited to the precise details of construction set forth, but desire to avail myself of such variations and modifications as come within the scope of the appended claim.

50 Having thus described my invention, what I

claim as new and desire to protect by Letters Patent is:

A box comprising two interfitting box sections with a wall of one of the sections providing a recessed area and a wall of the other section a slotted portion providing a yieldable tab, means for latching the box sections in interfitting relation with respect to each other with the recessed area in said one of said sections in registration with the slotted portion provided in the other section, said means comprising a resilient substantially U-shaped member removably mounted in the recessed area and insertable in the slot and frictionally engaging adjacent portions of the said walls, the tab provided by said slotted portion frictionally bearing against said member.

WILLIAM TROGMAN.
